UNITED STATES PATENT OFFICE.

STERLING ELLIOTT, OF NEWTON, MASSACHUSETTS.

DESIGN FOR A REACH FOR BICYCLES.

SPECIFICATION forming part of Design No. 22,671, dated August 1, 1893.

Application filed December 5, 1892. Serial No. 454,175. Term of patent 14 years.

To all whom it may concern:

Be it known that I, STERLING ELLIOTT, a citizen of the United States, residing in Newton, in the county of Middlesex and State of Massachusetts, have invented and produced a new and original Design for a Reach for Bicycles, of which the following is a specification, reference being made to the accompanying drawing, forming a part thereof.

10 The figure is a side view of my newly designed reach for bicycles.

The design consists in the rod *a*, curved continuously in one direction from the point 1 to the point 2, then curved in the opposite direction from the point 2, to the point 3, from

15 which point it extends upwardly in a straight

line at a slight rearward inclination and having the rod *b* located at a little distance below and curved in parallelism therewith from the point 4, to the point 5, then curved in the opposite direction from the point 5 to the point 6, and terminating in a horizontal cross piece *c*.

I claim—

The design for a reach for bicycles, substantially as herein shown and described. 25

In testimony whereof I have signed my name to this specification in the presence of two subscribing witnesses.

STERLING ELLIOTT.
